James D. Wilson, of the State of Connecticut May 10, 1804

Letters Patent May 10, 1804.

The Schedule is found to be in the Letters Patent and making part of the same, containing a description of the works of the said James D. Wilson himself of his Machine to cut along the ship's planks to make ship's staves & staves.

The Machine is made in the following manner: It is a solid four piece of wood, resembling a heavy jawbone with a lip on the side next the workman, a lip prevents the work from sideways to engine the ship in width. Then about one third of the length from the fore end is mounted, a wide cutting iron set very sloping, about forty degrees. Then set in a piece of wood, beech or other hard wood, inserted five or more cutting blades, as beas with the workman, about one inch long, resembling a barrel, set in a mortice after the manner of Dykes. The space between each cutting blade must be filled with wood or metal of suitable thickness to make the width of the ship. The blades must be fastened with a wedge or screw so as to be taken out for sharpening etc. Then so set they are secured in again about two or three inches forward of the cutting iron, so that the flat sides of the blades stand parallel with the side of the work of one in eight at the points about one eighth of an inch. The blade must be inward by one quarter at the forward in the sides, and at the top at the hind end. This machine is operated by two persons. In order to operate by one person, the small cutting blade must be set in a piece of wood about six inches wide, so as to have a shoulder to run against the side of the timber sufficient to steady it, and is used first and conveniently to divide all the slope to an equal width. Then the above described machine without the cutting blades following takes it off to an even thickness.

The wood should be first prepared by making it of an even thickness. Green wood is preferable to dry and white poplar is the wood commonly used.

James D. Wilson

Worship of God, and I thank God daily (for my life)
